J. MELNICK.

FOOTREST FOR ROCKING CHAIRS.
APPLICATION FILED JAN. 26, 1918.

1,314,089.

Patented Aug. 26, 1919.

UNITED STATES PATENT OFFICE.

JOSEPH MELNICK, OF BAYONNE, NEW JERSEY.

FOOTREST FOR ROCKING-CHAIRS.

1,314,089.

Specification of Letters Patent. Patented Aug. 26, 1919.

Application filed January 26, 1918. Serial No. 213,890.

To all whom it may concern:

Be it known that I, JOSEPH MELNICK, a subject of Russia, and resident of Bayonne, in the county of Hudson and State of New Jersey, have invented certain new and useful Improvements in Footrests for Rocking-Chairs, of which the following is a specification.

This invention relates to an adjustable 10 foot rest for chairs and its organization comprises among its novel features manually operated means to locate the foot-rest in place and an automatically operated counterbalance for the foot rest.

15 In the accompanying drawings Figure 1 shows a fragmentary elevation of a rocking chair for one form of the foot rest with its appurtenances connected therewith; Fig. 2 shows a partial top plan view of Fig. 1 and a section of Fig. 1 on the line 2, 2; Fig. 3 is a section of Fig. 1 on the line 3, 3; Figs. 4 and 5 represent top plan views of elements of the invention; Fig. 6 shows an enlarged section of Fig. 1 on the line 6, 6; Fig. 7 shows a lefthand side view of Fig. 6; Fig. 8 is a top plan view of Fig. 7 and Fig. 9 shows an end view of some details.

The rocking chair is represented with the runners 20, the uprights 21, 22 and the 30 seat 23.

A movable frame comprises the side bars 24 connected by the cross brace 25 with the lug 26 and the cross brace 27. Cross bars 28 and 29 extend between the side bars 24. Pins 30 extend from the top faces of the side bars 24. Bands 31 have their ends supported on the cross bars 28 and 29. A foot plate 33 is supported on the bands 31. A swinging foot frame comprises the main 40 portion with the side bars 34 and the cross bars 35, 36 which support the wicker-work 38. To the cross bar 36 is hinged the foot piece 40 with the wicker-work 41. The ends of the side bars 34 have the openings 42 that 45 are engaged by the cross bar 28. Chains 43 connect the outer ends of the side bars 34 and the upper end of the uprights 21.

Upon the runners 20 are supported adjustable brackets designated in their entirety by the numeral 45. Each of the brackets 45, comprises a U-shaped base frame with the roof 46 and the legs 47 and 48. A lug 49 with an opening 50 extends up from the roof 46. An adjustable box 55 shaped supporting guide 51 has the roof 52 with the opening 53. A spindle 54 extends

from the guide 51 and is clamped in different positions in the opening 50 by means of a clamping screw 55, which is in threaded engagement with the crown of the lug 49. 60 The leg 48 carries in threaded engagement the adjusting bolt 60 with the disk head 61 at one end and the slotted head 62 at the other end. A clamping plate comprising the members 63 and 64 is supported on the 65 head 61.

To the runners 20 are fastened guide brackets 68 which have extending therefrom legs 69 and 70, with opening for screws 71. A counterweight 72 having formed therewith the lug 73 is slidably supported in guide brackets 68.

A lazy-tong 75 has one end connected to the lug 73 and the other end to the lug 26.

To the lower face of the seat 23 are fastened a pair of bifurcated journal brackets 80 that have supported therein a rod 81. Between the legs of each bracket 80 there is fastened to the rod 81 an adjusting arm 82 that has formed therein an oblong opening 83. A top piece 84 is fastened to each arm 82 and has extending therefrom a pair of operating handles 85. The lower end of each arm 82 has formed therewith the side plates 86.

When the foot rest is not in use the swinging foot frame, having the side bars 34, is swung in the direction of the arrow A to be supported upon the foot plate 33, so as to be located out of the way, and under the 90 seat 23. When the foot rest is to be used the operator bears down on the handles 85, to move the arms 82 in the direction of the arrow B. By so doing the arms 82 bear against the pins 30 and the frame with the 95 side bars 24 is moved in the direction of the arrow C. Next the swing foot frame having the side bars 34 is swung in a direction opposite to the arrow A so that it will bear on the cross brace 27, and have its end supported by the chains 43. After the arms 82 have contacted with one pair of pins 30, they are raised over the next succeeding pair of pins 30 and made to bear against the latter to again move the frame having the side 100 bars 34. The arms 82 are enabled to be raised by reason of the elongated openings 83. To locate the foot rest in its unused position the arms 82 are moved in directions opposite to the arrow B. When the frame 110 with the side bars 24 is moving in the direction of the arrow C the counter weight 72

through the intervention of the lazy-tong 75 is moved in the direction of the arrow D so as to counterbalance the foot rest.

A bracket 90 is fastened to the runners 20 5 and the middle portion of the lazy-tong bears thereon. A pin 91 connects the middle portion of the lazy-tong and bracket 90. It will be noted that by means of the adjustable guides 51 the frame with side bars 10 24 can be used with chairs having runners like 20 that are different distances apart.

To the forward end of each of the runners 20 is hinged an arm 95. An opening 96 is formed in each of said runners, and in the 15 latter is located a spring 97 with one end bearing against the bottom of said opening and with the other end thereof fastened to the swinging end of said arm. The arms and springs counterbalance in a degree the 20 weight of the foot plate 33 and the side bars 24, with their appurtenances when they are located in their outward and extended positions.

Having described my invention what I 25 desire to secure by Letters Patent and claim is:

1. In a foot rest the combination of a movable frame, a foot plate for the frame, means to move the frame, a counterweight 30 35 coacting with the frame and a lazy-tong interposed between the counterweight and frame.

2. In a foot rest the combination of brackets adapted to be clamped to a chair, 35 a supporting guide supported in each bracket, a movable frame having side bars slidably supported in the supporting guides, pins extending from the side bars, adjustable arms pivoted above said side bars, side 40 plates formed with the arms and straddling the side bars, and handles on the arms to op-

erate them and cause their lower ends to abut against said pins and thereby move the movable frame.

3. In a foot rest the combination of mov- 45 able brackets adjustably clamped to the runners of a chair, a supporting guide carried in each bracket, means to adjustably fasten the supporting guide in different positions in each bracket, a movable frame with side 50 bars slidably supported in the supporting guides, pins extending from the side bars, a pair of adjustable arms pivoted above the side bars and adapted to have their lower ends engage said pins to move the movable 55 frame, guide brackets fastened to said runners, a movable counterweight supported in the guide brackets and a lazy-tong connecting the movable frame and counterweight.

4. The combination in a chair of runners 60 therefor, a movable frame for the runners, means for operating the movable frame, a counterweight coacting with the frame at one end of the chair and a counterbalance 65 coacting with the runners at the other end of the chair.

5. The combination in a chair of runners therefor, a movable frame with a foot rest movably connected to the runners, means to operate the movable frame, a counter- 70 weight coacting with the movable frame at the rear end of the chair, a plate hinged to each runner at the front end thereof and a spring bearing between the swinging end of the runner and plate.

Signed at Bayonne in the county of Hudson and State of New Jersey this 5th day of January A. D. 1918.

JOSEPH MELNICK.
